UNITED STATES PATENT OFFICE.

CLARENCE H. HOWARD, OF ST. LOUIS, MISSOURI.

CAR-UNDERFRAME.

No. 921,112.

Specification of Letters Patent.

Patented May 11, 1909.

Application filed December 24, 1908. Serial No. 469,126.

To all whom it may concern:

Be it known that I, CLARENCE H. HOWARD, a citizen of the United States, residing at St. Louis, in the State of Missouri, have invented 5 a new and useful Improvement in Car-Underframes, of which the following is a specification.

My invention relates to a cast metal car underframe particularly adapted for a self-clearing ore, or analogous dump-car having side hinged drop-doors, and has for its object 10 to provide a strong, rigid, and durable underframe of this class in which the metal surrounding the discharge openings there-through is disposed to the best advantage for resisting the lateral stress or spread of the load thereat.

The invention consists in features of novelty as hereinafter described and claimed, 20 reference being had to the accompanying drawing forming part of this specification, whereon,

Figure 1, is a top plan view of my improved underframe as applied to a self-clearing dump-car having side hinged drop-doors, 25 omitting the car body; Fig. 2, a vertical longitudinal section thereof on line 2, 2, in Fig. 1, and corresponding section through the car body thereon; Fig. 3, a vertical transverse 30 section to enlarged scale through the underframe and car body on line 3, 3, in Fig. 2, showing the side hinged drop-doors, and Fig. 4, a side elevation of the middle portion of the underframe and car body (broken away) at 35 and adjacent to the said doors.

Like letters and numerals of reference denote like parts in all the figures.

a represents my improved car underframe which is composed preferably, of cast steel 40 integral throughout and may be of any suitable design as to the number, arrangement, and cross section of its component members, comprising in the present case preferably, two opposite channel longitudinal side mem- 45 bers 1, a channel member or end sill 2 uniting the side members 1 together at their respective ends and having its middle portion preferably box-shaped and adapted thereto to increase the resistance of the underframe to 50 end shocks, a transverse preferably I-shaped member 3 adjacent to each end sill 2 and united at each end to the corresponding side member 1 and constituting the body-bolster of the car, adapted for the application there- 55 to of a suitable draft-gear, such as *b*, as seen to the left in Figs. 1 and 2, two opposite lon-

gitudinal channel members 4 intermediate to the side members 1, one on each side of the longitudinal center of the underframe *a*, and uniting the transverse members 2 and 3 together, and a middle longitudinal preferably I-shaped member 5 uniting the transverse members 3 together and forming therewith the openings *c* through the underframe *a* for receiving the lower portion of the hopper *d* of the car body as hereinafter more particularly referred to. Each side member 1 is united laterally to the middle longitudinal member 5 by two opposite transverse members 6, one on each side of the center of the underframe *a*, each member 6 being practically Z-shaped, or otherwise adapted in cross section, to receive the bottom edge portion of the corresponding inclined end wall 7 of the hopper *d* and forming thereto a rigid 65 brace to the longitudinal members 1 and 5 for resisting the lateral or spreading pressure of the material within the hopper *d*.

The bottom of the hopper *d* is formed longitudinally in the middle by an inverted V-shaped flooring 8 which is arranged directly over and along the middle longitudinal member 5, and united at its ends to the inclined end walls 7 of the hopper *d*, the inclined side walls of the flooring 8 being fixed to and supported by intermediate correspondingly shaped brackets 9 secured to the top of the middle member 5 at suitable intervals along the same, by bolts 10, or in any other suitable manner. Within the inverted V-shaped space thus formed between the flooring 8 and the top of the middle member 5 is mounted the longitudinal shaft 11 with its bearings 12 and drum 13 for the chains 14 (whereby the drop-doors *e* are 95 operated), which being of the ordinary well-known construction and forming no part of my invention need no further description.

For permitting free movement of the chains 14 over the outer lateral edge portions of the middle member 5, I form the latter thereto with recesses 15 having rounded faces 15' for engagement by the chains 14, which are thereby prevented from chafing and undue wear, and the opening and closing 100 of the doors *e* facilitated. The drop-doors *e* for closing the openings 16 which are formed, respectively, through the bottom of the hopper *d* on each side of the middle member 5 between the latter and the opposite portion 110 of the side member 1 and the corresponding transverse members 6, are preferably hinged

to the underside of the side members 1, the lugs or fixed portions 17 to which each door is pivoted by pins 18, being integral with the corresponding side member 1 as shown.

5 In the above construction, by uniting the ends of the transverse members 6 to the side and middle longitudinal members 1 and 5, and thereby forming solid sill frames around the outlet openings 16 of the hopper *d*, the 10 rigidity and resistance to spreading of the underframe *a* thereat are greatly increased and positive uniform closing of the drop-doors *e* insured at all times. It is here noted that in Fig. 3 one of the drop-doors *e* is shown 15 in its open position for the purpose of clearly indicating the configuration of the transverse members 6 at their bottom edges against which the doors *e* bear when closed, although in practice both doors *e* are opened 20 or closed simultaneously.

What I claim as my invention and desire to secure by Letters Patent is:—

1. In a car underframe of the character described, the combination of the side members, the end sills, transverse members uniting the side members together and adapted to form the body-bolsters of the car, a middle longitudinal member uniting the said transverse members together, and two opposite 25 transverse members integral with and uniting the middle member to each side member and adapted therewith to support the corresponding part of the lower end of a hopper and to form the walls of an outlet opening 30 35 from the said hopper through the said frame, substantially as described.

2. In a car underframe of the character described, the combination of the side members, the end sills, transverse members uniting the side members together and adapted for the application thereto of suitable draft-gear, a middle longitudinal member uniting the said transverse members together, and two opposite transverse members integral with and uniting the middle member to each side member and adapted therewith to support the corresponding part of the lower end of a hopper and to form the walls of an outlet opening from the said hopper through the said frame, substantially as described. 40 45 50

3. In a car underframe of the character described, the combination of the side members, transverse members uniting the side members together, a middle longitudinal member uniting the said transverse members 55 together, and two opposite transverse members integral with and uniting the middle member to each side member and adapted therewith to support the corresponding part of the lower end of a hopper and to form the walls of an outlet opening from the said hopper through the said frame, substantially as described.

4. In a car underframe of the character described, lugs integral with a side member 60 of the said frame and adapted for hinging the drop-door of a hopper thereto, substantially as described. 65

CLARENCE H. HOWARD.
